ANCHORING MEANS FOR ABRASIVE DISKS

Roger H. Homeyer, Tonawanda, N. Y., assignor to
The Carborundum Company, Niagara Falls,
N. Y., a corporation of Delaware

Application April 6, 1945, Serial No. 536,929

4 Claims. (Cl. 51—209)

1

This invention relates to the manufacture of abrasive articles. More particularly it relates to bonded abrasive articles such as grinding wheels or discs of the type which are secured at the flat side surface of the article to a suitable mounting plate or frame for support and/or reinforcement during use. The invention is especially concerned with the anchoring means provided in such abrasive articles for mounting them on their supports; it also pertains to methods of making wheels or discs of the described type which, when warpage or distortion of the abrasive body takes place during the process of making, and especially during the firing or curing of the article to its matured condition, will permit the mounting face of the wheel to be facilely dressed to an acceptable flatness within the tolerance necessary to provide a strong and firm attachment of the wheel or disc to its supporting plate or frame with the anchoring means firmly and strongly retained in position.

According to the present invention, a bonded abrasive wheel or disc adapted for mounting on a flat side face thereof is provided with anchoring means embedded in the bonded abrasive body and substantially flush with the mounting face of the article. The anchoring means consists of a strong and tough metallic insert, such as a threaded steel nut, and a relatively thin washer of softer material, the latter being located between the metal insert and mounting surface. The material of the washer is such that, if it is found necessary due to warpage during fabrication to lap or otherwise dress the mounting surface of the abrasive article to provide a suitably flat face for mounting, the washer will be worn down evenly with the surrounding bonded abrasive body and will not become separated from the contacting abrasive body by voids or cracks.

In order that the invention will be more clearly understood and for illustrative purposes, reference is made to the accompanying drawings, in which:

Figure 1 is a rear plan view of a grinding disc embodying the present invention, and showing the mounting plate partially broken away;

Figure 2 is a vertical cross-sectional view through the line 2—2 of Figure 1;

Figure 3 is a vertical cross-sectional view through an anchoring means of the type embodied in the disc shown in Figures 1 and 2 together with that portion of the abrasive body surrounding the anchoring means, and depicts in exaggerated form the manner in which a part of the anchoring assembly during dressing is

2

worn down even with the surrounding bonded abrasive body to provide a flat external surface.

Referring further to the drawings, Figures 1 and 2 depict an abrasive grinding disc adapted for side grinding and made in accordance with the teachings of the present invention. The abrasive disc illustrated in Figures 1 and 2 consists of an annular bonded abrasive body 4 having a flat side grinding face 5 and an opposite flat supporting face 6. The bonded abrasive body may be any desired dimension, the diameter of such articles differing over a wide range of sizes; wheels or discs of the described type are usually several inches thick so as to provide an article of relatively long useful life. The bonded abrasive body 4 is composed of abrasive grain such as crystalline aluminum oxide, silicon carbide, or other granular abrasive material of the desired grid size or sizes, suitably bonded.

10 The bond may be a vitrified ceramic material, or it may be a silicate, or a resin, or a natural or synthetic rubber compound.

As a support or means for mounting upon a grinding machine the abrasive body 4 is provided with a steel or other strong rigid backing plate 7 attached to the flat face 6 of the abrasive body 4 by means of anchoring bolts which are screwed into anchoring means 8. The backing plate 7 is provided with a central arbor hole 9 and three bolt holes 10 for fastening the backed disc to a mounting plate on the grinding machine. (The corresponding mounting plate for the grinding machine is not shown.) Although the abrasive disc as shown in Figures 1 and 2 is presented as attached to its mounting plate, it is customary for the bonded abrasive body to be fabricated by the manufacturer and supplied to the user who attaches the mounting plate 7 at the time and place of use. The mounting plate 7 is attached to the bonded abrasive body by means of anchor bolts 13 which screw into and engage the threaded metal inserts 11 of the anchoring means 8. Alternatively a stud may be screwed into the insert 11 and a nut placed on the outer end of the stud after the disc has been put onto the supporting plate 7.

A modified form of anchoring means wherein the metallic insert need not be threaded may be employed in that type of reinforced abrasive wheel or disc in which the disc is secured to the backing plate by bolts inserted in the wheel through holes extending from the front grinding face of the wheel completely through the abrasive body and engaging a similar unthreaded anchoring insert and threading into the backing plate

itself. However, as in the case of the specific abrasive disc herein illustrated, the metallic insert of the anchoring means is inset from the mounting face of the wheel and provided with a non-metallic composition washer or filling material between the metallic insert and the mounting face. The anchoring means 8 are embedded in the bonded abrasive body 4 in such position that the bottom side of the anchoring means lies flush with the mounting face 6 of the abrasive body. The number of these anchoring means embedded in any particular wheel or disc depends largely upon the size of the wheel, but also upon the conditions under which the wheel is to be used such as the speed of operation, severity of the grinding operation, etc. They are distributed over the mounting face of the wheel and are usually evenly spaced from one-another.

Each anchoring means consists of a strong, tough, threaded metal insert 11, as, for example, a tapered steel nut, and a softer, more easily abradable washer 12. The metallic insert 11 is preferably tapered and positioned with the large end of the insert farthest away from the mounting surface of the wheel or disc so as to be more strongly gripped by the surrounding abrasive body. Instead of tapering the metal insert the outer sides may be provided with a series of circumferential corrugations or otherwise provided with an uneven contour at the sides to enhance the gripping action of the bonded abrasive body on the insert. The washer 12 is made of softer material than the metal insert and is placed between the metal insert 11 and the mounting face 6 of the wheel and flush with the latter. A composition washer which has been found highly satisfactory for the purpose is a plain unthreaded "Tempered Masonite" washer $\frac{1}{8}$ " thick. ("Tempered Masonite" is a trade mark of the Masonite Corporation for material consisting of processed wood fibers compressed by heat and pressure and bonded by the resinous content to a strong, hard condition.) Other materials can be used provided that they stand up under the temperatures employed in maturing the bond of the abrasive body during the making of the article, and have the property of wearing away at a substantially equal rate with the surrounding abrasive body when the two are subjected to a lapping or comparable dressing operation. Materials which may be used for washers include various organic compositions such as various fibrous materials, synthetic resins, natural and synthetic hard rubbers, asbestos-cloth base phenolic material, and the like. The kind of material used for the washer will depend mostly on the nature of the bond of the abrasive body.

In making an abrasive article of the herein described type, such as that shown in Figures 1 and 2, the desired number of anchoring means, including composition washers and metal inserts are positioned in a suitable mold and the desired mixture of granular abrasive and bond therefore placed in the mold about the anchoring means. If desired, the washers may be cemented to the metal insert prior to positioning in the mold assembly, a suitable cement for such purpose being a liquid phenolic condensation product resin thinned with a suitable solvent. Before introduction of the abrasive mixture into the mold about the anchoring means, the latter are preferably coated with a thin liquid cement such as that sometimes used in cementing the washer to the metal insert. The mass is then pressed to the desired density and heated to mature the

bond for the abrasive article and also any auxiliary cementing or bonding means used in securing the anchoring means. In the case of organic bonds the bond may be partially or completely cured during the pressing operation although final cure is usually effected by an oven treatment at elevated temperatures following the removal of the formed article from the mold.

Instead of using a preformed composition washer and molding it into place along with the metal insert simultaneously with the molding of the bonded abrasive body, a modified procedure, particularly adaptable to the fabrication of ceramic bonded abrasive wheels and discs of the herein described type requiring a high temperature firing to mature the bond, may be followed. According thereto, the bonded abrasive body as molded and fired is provided with reentrant portions or cavities adjacent the intended mounting face and positioned the same as the anchoring means which are to be embedded therein but slightly larger in size than the latter. These holes or cavities may be provided by molding the abrasive body about removable inserts of the desired size placed in the mold prior to molding or about inserts which are readily decomposable at the temperature of firing. Such cavities may also be provided by molding the abrasive body in solid form and drilling or otherwise forming the cavities while the bond is still in the unfired state. After the bonded body has been matured, and before or after the mounting face has been dressed to a substantially flat condition, the metal inserts and washers are placed in position in the cavities and grouted in place by means of a suitable cement such as a liquid reactive phenolic resin capable of cold setting with acid hardener and usually mixed with some inert filler such as flint, fused quartz, air-floated asbestos, etc. Ceramic bonded wheels or discs constructed by this method may have the inserts grouted with lead or a similar soft metal or alloy and the composition washers inserted and grouted in place with a suitable organic cement as, for example, that given below. Grouting of the inserts in this modified method for ceramic wheels is preferably carried out with organic cements or alloys melting at a temperature lower than the melting point for lead since grouting with molten lead tends to warp the abrasive body. However, after grouting of the inserts and washers in place the mounting face of the abrasive disc can again be dressed flat, if necessary.

When abrasive wheels or discs are provided with anchoring means according to the above modified procedure, the preformed composition washers can be replaced by filling the intervening space between the mounting face and the metal insert normally occupied by the preformed washer with an organic hardenable composition such as a resinous cement such as that described above which will have substantially the same property of wearing away when abraded as do the preformed washers. When such compositions are used in place of the preformed washers it is necessary to protect the threaded portion of the metal inserts from being filled or smeared with the filling composition by temporary insertion of a plug which can be removed after the filler material has hardened.

It is not unusual for the resulting abrasive body to be slightly warped or distorted during the curing or firing operation. Such warpage is highly undesirable since a warpage as slight as two or three thousandths of an inch is sufficient to in-

terfere with satisfactory mounting of the body on its supporting plate. The larger the wheel or disc being made the more troublesome the warping or distortion problem becomes. In order to avoid the necessity of discarding warped wheels of this type efforts are made to lap or otherwise dress the mounting face of the warped article to an acceptable degree of flatness for mounting.

Figure 3 is an exaggerated fragmentary view of an abrasive wheel structure made in accordance with the present invention and embodying anchoring means of the type herein described consisting of a tough insert 11 and a washer 12 of softer material. The anchoring means in Figure 3 is shown after it has been submitted to a dressing or lapping procedure to remove warpage of the article. The composition washer 12 has been worn down even with the surrounding abrasive body 4 so that the mounting face 6a, including the external surface 12a of the washer, is flat and free from any projecting portions. It is to be understood that the excessive tilt of the anchoring means as shown in Figure 3 is thus pictured for purposes of clarity and the actual warpage which takes place is often up to $\frac{1}{8}$ ", which however must be removed if the article is to be rendered suitable for use.

As is clear from the above description, the present invention not only provides an abrasive wheel adapted for mounting on a flat side face but also a method of reclaiming those wheels of the herein described type which become warped or distorted during processing, and which if otherwise constructed would either have to be discarded or at least restricted to much lighter usage because of poor mounting ability or weakening of the anchoring assembly during subsequent dressing operations.

Having described the invention in detail it is desired to claim:

1. An abrasive article comprising a bonded abrasive body having a grinding surface and a substantially flat mounting face, said bonded abrasive body having embedded therein and substantially flush with said mounting face a plurality of anchoring means, each of said anchoring means comprising a metallic insert and a non-metallic washer, the latter being disposed between the metallic insert and the surface of said mount-

ing face and substantially flush with the latter surface.

2. An abrasive article comprising a bonded abrasive body having a grinding surface and a substantially flat mounting face, said bonded abrasive body having embedded therein and substantially flush with said mounting face a plurality of anchoring means, each of said anchoring means comprising a steel insert and a non-metallic washer, the latter being disposed between the metallic insert and the surface of said mounting face and substantially flush with the latter surface.

3. An abrasive article comprising a bonded abrasive body having a grinding surface and a substantially flat mounting face, said bonded abrasive body having embedded therein and substantially flush with said mounting face a plurality of anchoring means, each of said anchoring means comprising a metallic insert embedded within said abrasive body and spaced inwardly of the abrasive body from the mounting surface of said abrasive body, the intervening space between said metallic insert and the mounting face being filled with an organic composition substantially as easily abradable as the surrounding abrasive body.

4. An abrasive article comprising a bonded abrasive body having a grinding surface and a substantially flat mounting face, said bonded abrasive body having embedded therein and substantially flush with said mounting face a plurality of anchoring means, each of said anchoring means comprising a metallic insert embedded within said abrasive body and spaced inwardly of the abrasive body from the mounting surface of said abrasive body, the intervening space between said metallic insert and the mounting face being filled with a heat hardenable resinous composition.
